(57) **CLAIM**

The ornamental design for a panel with the appearance of board and batten as shown and described.

DESCRIPTION

FIG. 1 is an upper perspective view of a panel with the appearance of board and batten of the present general inventive concept;

FIG. 2 is a lower perspective view of the panel with the appearance of board and batten of FIG. 1;

FIG. 3 is a right side elevation view of the panel with the appearance of board and batten of FIG. 1;

FIG. 4 is a left side elevation view of the panel with the appearance of board and batten of FIG. 1;

FIG. 5 is a bottom plan view of the panel with the appearance of board and batten of FIG. 1;

FIG. 6 is a top plan view of the panel with the appearance of board and batten of FIG. 1;

FIG. 7 is a front elevation view of the panel with the appearance of board and batten of FIG. 1; and,

FIG. 8 is a rear elevation view of the panel with the appearance of board and batten of FIG. 1.

The appearance of any portion of the panel with the appearance of board and batten between the break lines shown forms no part of the claimed design.

1 Claim, 6 Drawing Sheets
